(57) **CLAIM**

The ornamental design for a sign, as shown and described.

DESCRIPTION

FIG. 1 is a front perspective view of a sign showing our new design;

FIG. 2 is a front view thereof;

FIG. 3 is a rear view thereof;

FIG. 4 is a side view thereof;

FIG. 5 is the opposite side view thereof;

FIG. 6 is a top plan view thereof;

FIG. 7 is a bottom plan view thereof; and,

FIG. 8 is an enlarged view of a portion thereof, taken from the encircled area in FIG. 2.

The shade lines in the Figures show transparency.

The stippling in the Figures shows contrast. By way of example, the areas with stipple shading may appear translucent.
